SPACED PLATE CIRCUIT INTERRUPTER

John A. Kalaway, Turtle Creek, Pa., assignor to
Westinghouse Electric Corporation, East Pitts-
burgh, Pa., a corporation of Pennsylvania

Application July 5, 1947, Serial No. 759,270

2 Claims. (Cl. 200—144)

1

This invention relates to circuit interrupters, in general, and more particularly to arc extinguishing structures therefor.

A general object of my invention is to provide an improved circuit interrupter of the spaced metallic plate type in which the arc is more readily moved into engagement with the several plates and therebetween to more rapidly effect its interruption.

A more specific object of my invention is to provide an improved circuit interrupter of the spaced magnetic plate type in which the venting means is so improved as to facilitate the entry of the arc between the plates and to minimize the back pressure of gases formed by the arc.

Still a further object is to improve the venting arrangement of an arc extinguishing structure of the foregoing type by symmetrically providing venting passages in such a manner that the length of the arc travel upon the several plates is not impaired.

Further objects and advantages will readily become apparent upon reading the following specification, taken in conjunction with the drawing, in which:

Figure 1 is a side elevational view, partially in section, of a 3-pole air break circuit interrupter embodying my invention and shown in the open circuit position;

Fig. 2 is a plan view of one of the slotted magnetic plates used in the extinguisher of Fig. 1;

Fig. 3 is a side elevational view of the plate shown in Fig. 2;

Fig. 4 is a plan view of the arc extinguishing structure of Figure 1, indicating the alignment of the notches provided in the several plates to provide venting passages along the rear of the extinguisher; and

Fig. 5 is an exploded view of several of the spaced magnetic plates to more clearly show the alignment of the notches provided in the plate structure.

Referring to the drawing, and more particularly to Fig. 1 thereof, the reference numeral 1 generally designates a 3-pole air break type of circuit interrupter to interrupt the three phases of the protected circuit. All three poles of the breaker are simultaneously opened by the actuation of an operating handle 2 which projects through a slot 3 in the cover 4 of the circuit breaker 1. The cover 4 is mounted upon the base 5 of the interrupter 1.

Considering one pole of the interrupter along one side thereof, the extinguishing structure of which is broken away to indicate the method of

2

arc rupture, it will be observed that a line terminal 6 is provided adjacent one end of the breaker 1. The line terminal 6 is electrically connected by a suitable configured strap 7 to a stationary contact 8, which, in the closed circuit position of the interrupter makes electrical engagement with the movable contact 10 of the interrupter. Preferably, the movable contact 10 is fixedly secured to a rotatable movable contact arm 11 actuated by any suitable fast operating mechanism generally designated by the reference numeral 12. The mechanism 12 forms no part of my invention and may be of any desired conventional type. It suffices to say the mechanism 12 actuated by operation of the handle 2 serves to simultaneously open the three poles of the interrupter 1 to break the three phases of the protected circuit.

Electrically connected to the conducting contact arm 11 is a conducting shunt 13 which makes electrical connection to a strap conductor 14, the latter leading to the left-hand line terminal 15 of the interrupter. As is well known by those skilled in the art, a suitable trip mechanism 25 may be interposed in the circuit to effect opening of the interrupter 1 in response to excessive current conditions in the protected circuit. The base 5 and the cover 4 are preferably formed of a suitably molded material such as Bakelite or the like.

During the opening operation, the upward separation of the movable contact 10 away from the stationary contact 8 establishes an arc, the initial position of which is designated by the dotted line 9. This arc 9 is extinguished by the operation of an arc extinguishing structure generally designated by the reference numeral 16, and consisting of a plurality of spaced slotted magnetic plates 17, the configuration of each of which is more clearly indicated in Figures 2 and 3. As shown in these figures, each plate 17 is preferably formed of magnetic material, in this instance, soft sheet steel. Each plate 17 has a converging slot 18 extending inwardly from one side 19 of the plate. Lugs 20 are preferably integrally formed with the plate 17 to permit its rigid attachment within a curved U-shaped fiber wrapper or enclosure designated by the reference numeral 21 and shown more clearly in Fig. 4. The fiber wrapper or enclosure 21 is made of fiber sheet material and is provided with a plurality of slots 22 through which project the lugs 20 of the plates 17. After the several plates 17 have been suitably positioned with their lugs 20 extending through the slots 22 of the fiber wrap-

per 21, at least some of the lugs 20 are swaged over to maintain the wrapper 21 and the several plates 17 together as a unit which forms a sub-assembly and is designated by the reference numeral 23 of Fig. 4. A steel arc runner 24 shown more clearly in Figs. 1 and 4 also has side lugs 20 which also project through suitable slots provided in the side walls of the fiber wrapper 21. Preferably, the arc runner 24 has a reverse bend at its left hand end, as indicated at 25, within which is positioned a plate 26 provided with a threaded aperture 27.

To maintain the extinguisher 16 in position relative to the circuit interrupter 1, it is only necessary to provide a screw 28, the upper end of which, as viewed in Figure 1, is threadedly secured into the threaded aperture 27 of the arc runner 24. This serves to rigidly fasten the sub-assembly 23 fixedly in position, and yet permits the ready removal thereof upon unscrewing the screw 28 from the arc runner 24.

The arc 9 which is initially established upon the separation of the movable contact 10 upwardly away from the stationary contact 8, is drawn magnetically toward the apex of the several slots 18 provided in the magnetic plates 17, as indicated by the arrow 29 of Fig. 4. When the arc 9 reaches the closed ends of the several slots 18, it is subdivided into a plurality of serially related arcs designated by the reference numeral 30 in Fig. 1. These short serially related arcs 30 continue to move toward the magnetic centers of the plates 17 as indicated by the arrow 31 in Fig. 4. The increased arc voltage due to the drop across the various cathode and anode terminals and the cooling and neutralizing of the hot ionized arc gas by the steel plates 17 extinguishes the arc.

We have found that the presence of the several serially related arcs 30 adjacent to the fiber wrapper 21, together with the heated air, tends to provide a back pressure of gas which inhibits the rapid movement of the short arcs 30 between the magnetic plates 17. It is desirable to keep the arc extinguisher 16 as small as possible to provide small dimensions for the interrupter 1. It is also necessary to maintain adequate clearance between the extinguisher 16 of one pole and the extinguisher 16 of the adjacently disposed pole. Furthermore, it is necessary to provide adequate length of arc travel "A" between the plates as indicated in Fig. 4. This is necessary so that the arcs 30 will not heat any particular portions of the plates 17 but are kept rapidly moving until interruption follows. Thus the length of travel "A" is important to provide proper arc travel.

Symmetrically notching each of the plates 17, as indicated at 32, provides upon alignment of the several notches 32, longitudinally extending venting passages generally designated by the reference numeral 33 in Fig. 4. The substantially symmetrical shape of the magnetic plates also provides magnetic flux paths which are substantially symmetrical about the center axes of the plates which act to keep the arc centered in the plate structure during its movement.

The provision of a space between each of the two corners of each plate and the surrounding insulating enclosure member 21 forms two symmetrically disposed venting passages 33 to permit the arc gases to pass from between each pair of plates freely along the extinguisher 16 to the upper end thereof as shown in Fig. 1. By the symmetrical positioning of the venting passages

33, however formed, the arcs 30 are not acted upon by unbalanced back gas pressures and are not deviated thereby from their straight line course as defined by the arrow 31 of Fig. 4. Furthermore, the notches 32, being at the sides of the center axis of the plates, do not shorten the amount of sheet plate material available to permit full length of arc travel along the center axis of the plates before interruption ensues. Another feature of this arc extinguisher is that there are no openings through the plates adjacent the path of arc movement so that the maximum number of short arcs is maintained between the plates, with the maximum number of cathode and anode drops and the maximum arc voltage.

I have found upon testing my improved arc extinguisher 16 that short circuit currents of 10,000 amperes and over may be successfully interrupted on voltages up to 250 volts direct current or 600 volts alternating current in a very small space. Without the vent passages 33, it was found that back-pressure of the gases formed by the heated air and also by gas evolved from the fiber wrapper 21 prevented the rapid movement of the several arcs 30 along the magnetic plates 17 in the direction of the arrow 31 of Fig. 4 and hampered interruption of the arc.

From the foregoing description of my improved extinguisher, it will be apparent that the symmetrical venting arrangement provides an arc extinguishing structure 16 of minimum dimensions without impairing the desired high speed arc movement between the plates 17. The two venting passages 33 provided upon alignment of the several notches 32 readily permit venting of the arc gases and direct them upwardly, as viewed in Fig. 1, away from the separated contact structure to minimize the possibility of re-striking. The venting passages 33 prevent the arc 9 from being blown back by the back-pressure of the gases formed and permitting it to restrike between the contacts 8, 10.

Although I have shown and described a particular structure, it is to be clearly understood that the same was merely for the purpose of illustration, and that changes and modifications may readily be made therein by those skilled in the art without departing from the spirit and scope

50 of the appended claims.

I claim as my invention:

1. A circuit interrupter including means for establishing an arc, an arc extinguishing means for extinguishing the arc including a plurality 55 of spaced conducting plates, each conducting plate having a single-ended slot extending inwardly from the front end of the plate and along the central axis thereof, an insulating enclosure substantially enclosing the rear ends of the plates, 60 each plate having a pair of notches provided therein at the rear corners thereof, the several notches aligning and cooperating with the insulating enclosure to define two continuous venting passages at the rear corners of the plates to minimize back pressure of the formed arc gases 65 and to prevent unbalanced gas pressure forces, and the portions of the insulating enclosure which bound on the two continuous passages being completely closed to confine the arc gases 70 within said continuous venting passages.

2. Arc-extinguishing means for a circuit interrupter including a stack of spaced conducting magnetic plates, each magnetic plate having a single V-shaped slot extending inwardly from the front end thereof, an insulating enclosure

substantially enclosing the rear portion of the sides and rear ends of the plates, each plate having a pair of notches provided therein at the rear corners thereof, the several notches aligning and cooperating with the insulating enclosure to define two venting passages extending continuously through the stack of plates at the rear corners of the plates to minimize back pressure of the formed arc gases and to prevent unbalanced gas pressure forces, and the bounding 10 portions of the insulating enclosure which bound on the two continuous passages being completely closed to confine the arc gases within said continuous venting passages.
